PAPER TACKING STRIP

Leslie F. Barnum, Detroit, Mich.

Application September 27, 1935, Serial No. 42,383

6 Claims. (Cl. 117—3)

This invention relates to a tacking strip formed of paper and constitutes an improvement on the tacking strip disclosed in my prior Patent No. 1,912,121, of which inspection is invited.

5 Tacking strips of fibrous material are used quite extensively in the manufacture of automobiles having steel bodies, the strips being secured in the bodies to provide means whereby tacks may be used for attaching upholstery thereto. The body parts are provided with channel members, with grooves, recesses and the like, into which the tacking member is secured by prongs or the like.

Originally tacking strips were formed by spirally twisting paper ribbons to provide a paper rope and the rope was subsequently pressed into a shape whereby it fitted into the recesses or grooves in the automobile body. Difficulty was experienced with this type of strip because of its 10 natural tendency to unwind, which caused it to assume a corkscrew shape. By making the tacking strip of oppositely twisted strands, as claimed in the above referred to patent, the difficulty experienced in connection with the original tacking strip was avoided. However, in the forming of automobile bodies by present day methods there are certain conditions wherein my patented 15 strip cannot be used without difficulty. For example, in some automobile bodies the tacking strip is placed in parts of the bodies prior to welding, and in other cases after the welding operation and prior to grinding away the flash. In these instances the strip is sometimes nicked by the grinding wheel, and when the patented 20 strip is nicked, particularly when it is in a groove which is not straight as for example, a groove around a window opening in a body, it frequently happens that one or more of the twisted strands are completely severed. The severing of a strand, 25 while the strand is under tension through bending of the strip, results in a tendency for the strand which is severed to unwind to such an extent that the two ends thereof project outwardly beyond the surface of the groove edges. 30 For this reason it is not acceptable to the automotive industry under these particular conditions because it requires an additional operation of removing the projecting ends.

The primary object of the present invention is 35 to provide a tacking strip suitable for use under the conditions recited and this is accomplished by forming the strip of oppositely twisted strands, the outside winding being formed of ribbons which are flat, unwrinkled, and which adhere to 40 the inside winding. The outside winding thus

constitutes a casing for the inside winding and because the outside winding is smooth and flat each strand thereof is of greater width than the inner strands, whereas in my prior patent all the strands were approximately the same size. 5 The particular formation of the outside winding eliminates the possibility of one of these strands being completely severed by a nick as above described. This invention therefore provides a sheath or casing secured around the spirally 10 twisted core by an adhesive so that it may be abruptly bent without spreading or parting of the strands and this sheath or casing functions to prevent the natural tendency of the core winding to partially unwind and cause the strip 15 to assume a corkscrew shape.

It has been found that moisture in the atmosphere affects the tacking strip and sometimes causes it to swell to such an extent that present day methods of assembly require that the strip 20 be waterproofed. To waterproof the strip the paper is impregnated with asphalt, which is the only commercially practical material known at present. However, asphalt acts as a lubricant 25 and when the tacks are driven into the strip they do not hold as efficiently as when the strip is not waterproofed. This invention has as another object to provide a tacking strip which is waterproofed and which includes means for efficiently holding the tacks. 30

In order to provide a waterproofed strip which will efficiently hold tacks the present invention provides a core for the strip which is formed of paper previously treated so that it will not absorb liquid asphalt readily. The spiral ribbons 35 and the spirally formed sheath are both treated with asphalt prior to the twisting operations and the core which does not absorb asphalt provides efficient means for holding the tacks because it lacks the asphalt which acts in the nature of a 40 lubricant. Due to the fact that the core paper is previously treated so that it will not absorb asphalt, the asphalt from the spirally twisted ribbons does not penetrate the same when the 45 rope is pressed into strip form by the pressing rolls. The core paper is of a hard fiber type commercially known as "kraft" paper.

With the above and other ends in view the invention consists in matters hereinafter more particularly pointed out with reference to the accompanying drawing, in which

Figure 1 is a vertical section of a machine for forming the present strip, and

Fig. 2 is a diagrammatic view of the strip.

In the drawing the numerals 1 and 2 designate 55

disks which are secured together by removable bolts 3 having sleeves 4 thereon. The disk 1 has a hollow spindle 5 rotatably received in a bearing 6 on a frame member 7. The disk 2 has a hollow spindle 8 rotatably received in a bearing 9 on a frame member 16. The disks 1 and 2 and the bolts 3 and sleeves 4 constitute a rotatable support for a plurality of rolls 11 of paper.

A pair of disks 12 and 13 are secured together by elements 14, preferably formed the same as the bolts 3 and sleeves 4. The disk 12 has a comparatively large hollow spindle 15 rotatably received in a bearing 16 on a frame member 17. The disk 13 has a spindle 18 rotatably received in a bearing 19 on a frame member 20. The disks 12 and 13 and the elements 14 constitute a rotatable support for a plurality of rolls 21 of paper. In addition, in this latter rotatable support, are provided guide elements 22 which are angularly positioned with respect to the axes of the support and the rolls 21 of paper. The function of the guides 22 will become apparent as the description progresses.

Spaced outwardly from the end of the spindle 8 is a pair of pressing rolls 23 and 24, the roll 24 having a groove 25 into which the roll 23 extends. Spaced outwardly of the end of the spindle 18 is a similar pair of rolls, respectively designated 26 and 27. The disk 27 has a circumferential groove 28 into which the roll 26 extends. Spaced outwardly from the end of the spindle 5 is a frame 29 supporting a shaft 30 upon which is received a roll 31 of paper.

A drive shaft 32 is rotatably supported by frame members and is adapted to be driven by a suitable motor (not shown). On the shaft 32 is provided a sprocket 33 which is connected by a chain 34 to a sprocket 35 on the spindle 8. A bevelled gear 36 is mounted on the shaft 32 and meshes with a similar gear 37 on a vertical shaft 38. On the upper end of the vertical shaft 38 is a gear 39 meshing with a gear 40 which is secured to the pressing roll 24. A gear 41 is mounted on the shaft 32 and meshes with a gear 42 on a shaft 43 supported by the frame 20. On the other end of the shaft 43 is a sprocket 44 which is connected by a chain 45 to a sprocket 46 secured on the spindle 18. A bevel gear 47 on the shaft 32 meshes with a similar gear 48 on a vertical shaft 49 having a gear 50 meshing with a gear 51 which is secured to the pressing roll 27.

Extending through the spindle 15 is a spray nozzle 62 having a supply line 63 with a control valve 64 therein. The spray device is for handling liquid adhesive in a manner and for a purpose to be presently described, the reservoir for containing the liquid adhesive and the means for forcing it to the spray gun not being shown here because such means are already well known in the art and they form no novel part of the invention here presented.

In operation a ribbon 52 from the roll 31 is extended through the spindle 5 and is drawn through the spindle 8, along with ribbons 53 from the rolls 11, by the rotatable rolling elements 23 and 24 when the power shaft 32 is rotated by a suitable motor. At the same time these ribbons are drawn through the spindle 8 the disks 1 and 2 are rotating, with the result that the ribbon 52 is crushed into a compact mass by the action of the ribbons 53 winding themselves around the same. A rope 54 is thus formed which consists of a crushed ribbon core with spirally wound ribbons wrapped around the same. As the rope 54 passes between the rolling elements

23 and 24 it is compressed into a compact strip 55. The strip 55 extends through the spindles 15 and 18 and is engaged by rolling elements 26 and 27 which function to propel the strip lengthwise. Between the disks 12 and 13, ribbons 56 from the paper rolls 21 are wound around the strip 55 by the rotating action of the disks 12 and 13.

It will be noted that the sprocket 35 on the disk 2 is directly connected to the sprocket 33 on the drive shaft 32 whereas the sprocket 46 is connected to the drive shaft 32 through the sprocket 44, shaft 43 and gears 42 and 41, with the result that the sprocket 46 is rotated in a direction opposite to the sprocket 35. The ribbons 56 are thus wound around the strip 55 in a direction opposite to the ribbons 53.

As the ribbons 56 are drawn from the paper rolls 21 they pass over the guiding elements 22 which function to hold the ribbons in a flat, un-wrinkled condition as they are wound around the strip 55. While the winding action of the ribbons 56 is taking place a liquid adhesive is sprayed onto the inside surface of the ribbons and onto the outside surface of the strip 55. The pressing rollers 26 and 27 press the ribbons 56 into firm contact with the strip 55 to insure adhesion.

Prior to treating the paper ribbons in the above described manner the paper of roll 31 is treated whereby it does not readily absorb asphalt. A hard surfaced, hard fibre paper, commercially known as "kraft" paper has been found satisfactory for this purpose. The paper of rolls 11 and 21 are impregnated with asphalt, preferably by running the ribbons through a bath of asphalt which is held in solution by heat. Asphalt rendered liquid by solvents is satisfactory but has the disadvantage of requiring considerable time for the solvents to evaporate.

Due to the fact that the ribbons 56 are secured by an adhesive to the strip 55 they may be punctured, as pointed out in the preamble, without the ends formed by the puncture tending to separate from the strip. The ribbons 56 are wide as compared with the windings of the ribbons 53 as may be readily seen upon reference to Fig. 2 wherein the progressive winding action is illustrated diagrammatically.

In cases where waterproofing is not essential the core of hard fibre paper permits the remainder of the strip to be formed of soft fibre paper by counteracting the inefficiency of a soft fibre strip as means for holding tacks.

Although a specific embodiment of the invention has been illustrated and described it will be understood that various changes may be made in the details of construction without departing from the spirit of the invention as defined by the appended claims and such changes are contemplated.

What I claim is:—

1. The method of forming a paper tacking strip which consists in spirally wrapping paper ribbons about a paper strip, compressing the formation provided by the wrapped ribbons and strip and forming the same into a reed, and spirally wrapping paper ribbons flat about the reed.

2. The method of forming a paper tacking strip which consists in crushing a paper core by winding paper ribbons spirally thereabout, compressing the formation provided by said core and ribbons into a reed, and spirally wrapping paper ribbons flat about said reed.

3. The method of forming a paper tacking strip

which consists in spirally wrapping paper ribbons about a paper strip, compressing the formation provided by the wrapped ribbons and strip and forming the same into a reed, and spirally wrapping a plurality of ribbons about the reed while maintaining the ribbons flat and in overlapped relation.

5 4. The method of forming a paper tacking strip which consists in crushing a paper core by winding paper ribbons spirally thereabout, compressing the formation provided by said core and ribbons into a reed, and spirally wrapping a plurality of ribbons about the reed while maintaining the ribbons flat and in overlapped relation.

10 5. The method of forming a paper tacking strip which consists in spirally wrapping paper rib-

bons about a paper strip, compressing the formation provided by the wrapped ribbons and strip and forming the same into a reed, spirally wrapping paper ribbons flat about the reed, and placing adhesive on the inside surfaces of the flat wound ribbons while they are being wound about the reed.

15 6. The method of forming a paper tacking strip which consists in crushing a paper core by winding paper ribbons spirally thereabout, compressing the formation provided by said core and ribbons into a reed, spirally wrapping paper ribbons flat about said reed, and placing adhesive on the inside surfaces of the flat wound ribbons while they are being wound about the reed.
